UNITED STATES PATENT OFFICE.

EDWARD B. HESS, OF MANHATTAN BEACH, NEW YORK, ASSIGNOR TO ROYAL TYPE-WRITER COMPANY, INC., OF NEW YORK, N. Y., A CORPORATION OF NEW YORK.

TYPEWRITING MACHINE.

Application filed November 9, 1922. Serial No. 599,863.

To all whom it may concern:

Be it known that I, EDWARD B. HESS, a citizen of the United States, residing in Manhattan Beach, in the county of Kings 5 and State of New York, have invented certain new and useful Improvements in Typewriting Machines, of which the following is a specification.

This invention relates to the paper tables 10 of typewriting machines which are provided with adjustable paper gages and margin scales for positioning the edges of the paper relatively to the printing point and for guiding the paper over the table in such 15 manner as to obtain the desired margin. Devices for this purpose are shown in my Patents 1,168,207 of January 11, 1916, and 1,417,903 of May 30, 1922, and in the pending application of Walter D. Camp, No. 20 560,707, filed May 13, 1922. In said application the table shown is provided with a margin scale plate secured in a recess at the left hand side of the table and the gage or paper guide is so mounted as to move 25 across the scale. No gage or paper guide is provided at the opposite or right hand end of the table and therefore no provision is made for regulating the margin there.

It is often desirable not only to regulate 30 the margin at the left hand end of the table, but also at the opposite end thereof. This is particularly the case when using cards and according to my invention, the table is provided with a scale which extends from 35 one end of the table to the other, and the table is also provided with paper gages for regulating both margins. Inasmuch as it is not generally necessary to regulate the right hand margin, provision is made for 40 moving the right hand gage from its operative position on the table to a position above the upper edge of the table or to a position behind the table when desired.

The scale, which as before stated, extends from one end of the table to the other, is calibrated and numbered in opposite directions from a zero point which latter is located nearer to one end of the table than to the other. The devices pivotally connecting one of the paper gages to the carriage are of novel construction and will be hereinafter more fully described.

In the accompanying drawings,

Figure 1 is a vertical section through parts

of a Royal standard typewriting machine, 55 with my improvements applied.

Figure 2 shows a rear elevation of some of the parts illustrated in Figure 1, the manner in which the view is taken being indicated by the arrows in Figure 1. 60

Figure 3 is a detail sectional view on the line 3—3 of Figure 1.

Figure 4 is a detail sectional view of some of the devices employed for pivotally connecting one of the paper gages with its support. 65

Figure 5 is a front elevation of the paper table equipped with the paper gages and the margin scale made in accordance with my invention, both gages being in operative 70 position.

Figure 6 is a similar view with one of the gages shown by dotted line moved to inoperative position.

Figure 7 is a view of the marginal scale 75 and stop.

Parts of the side plates of a typewriter carriage frame are indicated at A. C represents a margin rail, and E a portion of a paper pan which latter is supported by a 80 frame piece F carrying a strip or pad G of felt or similar soft material which serves as a cushion for the table when swung from its raised to its working position.

The paper table T is carried by two supporting arms H which are preferably pivotally mounted to turn about the longitudinal axis of the tabular rail D as in the standard Royal machine. 85

The table is provided with a scale K which 90 extends from one end of the table to the other. This scale may be applied to the table in any suitable way, but preferably the graduations and numbers are formed on or applied to a metal strip arranged in a 95 recess or depression in the table. The opposite ends of the scale plate or metal strip extend through openings t in the table as shown and as more fully described in the application of Walter D. Camp above referred to. In view of the length of the metal strip and in order to prevent buckling thereof the middle portion of the strip is provided with devices for adjustably securing it to the table. These devices may consist of a short bolt t' extending through a slot t² in the table and provided with a tightening nut t³. 100

105

The scale K bears numbers running in opposite directions to the right and to the left from a zero point, which is located nearer to one end of the table than the other—5 preferably near the left hand end as shown.

The paper gage M at the left hand of the table is similar in construction to that shown in the application of Walter D. Camp above mentioned and operates in a similar 10 way. This gage is supported on a tie rod N extending from one side of arm hinged to the carriage frame to the other. It is adjustable transversely across the table to the desired extent, but no provision is made for 15 giving it other adjustments, as other adjustments are not as a rule required at the left hand end of the table. The right end gage O, however is so constructed and mounted that it may be adjusted lengthwise of the 20 table to the desired extent and may also be moved from operative position to inoperative position above the table top, or to a position in rear of the table. For this purpose the gage is pivotally connected at q 25 with the arm q' of a bracket Q which is mounted to slide on the tie rod N. As clearly shown in Figure 1, the lower end of the bracket Q is formed with a recessed portion r , which fits one side of the tie rod and 30 the bracket is held in place on the rod by a clamp plate R recessed at r' , to fit the tie rod, and having an upper portion which is bolted to the bracket Q, at R'. The clamp has a lower portion or arm r^2 , which serves 35 to retard the rearward movement of the gage when the latter is swung rearwardly to the dotted line position shown.

The devices shown for pivotally connecting the gage O with the bracket Q are of 40 novel construction permitting the gage to be readily turned from operative to inoperative position, and yieldingly held in either position. The gage O is formed at its upper end with a lug or arm o which carries a rearwardly extending pin or arm s threaded at the outer end to receive the hollow nut S enclosing a spiral spring U which surrounds the pin. The arm q' of the bracket is formed with a central opening through which the 45 pin s extends and in which is supported a block V in which the pin turns. The rear end of the block V is formed with a series of recesses v adapted to receive antifriction balls W which are held in place by a disc X 50 having openings α into which the balls W project. The spring U yieldingly holds the disc in engagement with the balls in such manner that they can not be dislodged from the recesses v in the block V.

60 The disc X can move to a limited extent endwise of the pin s but it is prevented from turning thereon by a lug or key α' , which projects from the disc and enters a longitudinal groove s' in the pin. By this construction the gage O is so supported as to

be properly held in its adjusted position and may be readily turned from operative position on the table to a position at the upper end thereof. In operation the disc X recedes to a small extent when the gage carrying the 70 pin and disc is turned to a new position and until the balls again enter the holes in the disc. In this way the gage O may be exactly adjusted and properly held in the 75 desired position.

The gage O may be merely moved to a position shown by the dotted line in Figure 6 at the upper edge of the table or, if desired, it may be moved to a position behind the table as indicated by dotted line in 80 Figure 1, the rearward movement of the gage being limited by the arm r^2 which abuts against the rear side of the table.

The arm N' shown in Figure 1 is a part of the device shown in the application of 85 Walter D. Camp for mounting the gage M.

While I have shown my invention embodied in a typewriting machine of the Royal standard type, it will be understood that it may be embodied in machines of 90 various kinds. As explained in the application of Walter D. Camp above mentioned, the paper gages are associated in such manner with the margin scale on the table and the margin scales on the margin stop bar that it is impossible to adjust the gage definitely a given number of scale spaces corresponding with the letter spaces on the machine. It is to be understood that the scale spacing of the scale plate K corresponds with the letter spaces on all other scales in the machine. The manner in which the gage is used may be understood from a single illustration. If the gage M is located at zero, and the margin stop C' on the machine is set at 10, it would indicate that there would be 10 spaces from the edge of the sheet to be written upon to a point where printing would begin, and if it be desired to add 105 five more letter spaces or to diminish the margin to that extent, it would be unnecessary for the operator to adjust the margin stop, it being only necessary to adjust the paper gage five spaces to the right and the printing would begin at that point. If the operator has a set or predetermined margin which is always adhered to in the usual width of paper, this relation can be assured and maintained at all times in case it is desired to move the gage to a position to the 110 right to use the paper narrower than the standard width, and where a set margin is still desired. In a similar way the gage O at the right hand end of the table may be adjusted over the scale to the right of the 115 zero point.

I claim as my invention:

1. A paper table having scale plate receiving openings near each end, and an intervening plate receiving recess in combination 120

with a scale plate seated in said recess, having its opposite ends extending through the openings at the ends of the plate and provided with devices for securing its middle 5 portion to the table.

2. A paper table having scale plate receiving openings near each end and an intervening recess in combination with an end- 10 wise adjustable scale plate seated in said recess, having its opposite ends extending through said openings, and provided with devices for adjustably connecting its middle portion to the table.

3. The combination with the paper table 15 of a typewriting machine of a paper gage having a supporting bracket mounted in rear of the table and an arm extending through the bracket, a bearing block carried by the bracket through which the arm ex- 20 tends, and devices carried by the arm for yieldingly resisting the turning movement of the arm.

4. The combination with the paper table 25 of a typewriting machine of a paper gage having a supporting bracket mounted in rear of the table and an arm extending

through the bracket, a bearing block carried by the bracket through which the arm extends, a disc movable endwise on the arm of the gage but held against rotary movement thereon, balls interposed between the disc and the bearing block and means for yieldingly holding the disc in engagement with the balls. 30

5. The combination with the paper table 35 of a typewriting machine of a paper gage having a rearwardly extending pin or arm, a bracket mounted to move lengthwise of the table which supports the gage, a bearing block supported by the bracket through 40 which the arm of the gage extends and which is formed with recesses at its rear end, balls mounted in said recesses, a perforated disc engaging the balls when mounted on the arm of the gage to turn therewith and 45 to slide longitudinally thereon, a recessed nut carried by the gage arm and a spring housed in said nut which presses the disc into engagement with the balls.

In testimony whereof, I have hereunto 50 subscribed my name.

EDWARD B. HESS.
